CLAIM

The ornamental design for a tire tread, as shown and described.

DESCRIPTION

FIG. 1 illustrates a front elevational view of a tire tread according to the present disclosure;

FIG. 2 illustrates a rear elevational view thereof;

FIG. 3 illustrates a first perspective view thereof;

FIG. 4 illustrates a second perspective view thereof;

FIG. 5 illustrates a right side elevational view thereof;

FIG. 6 illustrates a left side elevational view thereof;

FIG. 7 illustrates a first fragmentary perspective view showing details of the thread portion thereof;

FIG. 8 illustrates a second fragmentary perspective view showing details of the thread portion thereof;

FIG. 9 illustrates a fragmentary enlarged view of Detail Z thereof;

FIG. 10 illustrates a fragmentary enlarged front view showing details of the thread portion thereof; and,

FIG. 11 illustrates a fragmentary enlarged view of Detail C thereof.

The ornamental design that is claimed is shown in solid lines in the drawings. In the drawings, the broken lines depict environmental subject matter only and form no part of the claimed design.
